UNITED STATES PATENT OFFICE.

CHARLES L. STARTUP, OF ELLENVILLE, NEW YORK.

ELEVATOR.

SPECIFICATION forming part of Letters Patent No. 679,484, dated July 30, 1901.

Application filed April 5, 1901. Serial No. 54,432. (No model.)

To all whom it may concern:

Be it known that I, CHARLES L. STARTUP, a citizen of the United States, residing at Elenville, in the county of Ulster and State 5 of New York, have invented certain new and useful Improvements in Elevators, of which the following is a full and complete specification, such as will enable those skilled in the art to which it appertains to make and use the 10 same.

This invention relates to elevators; and the object thereof is to provide an elevator-car with attachments which will operate in the case of an accident or if the rope or cable 15 breaks to prevent the falling of the car.

With this and other objects in view the invention consists in the construction, combination, and arrangement of parts hereinafter described and claimed.

20 The invention is fully disclosed in the following specification, of which the accompanying drawings form a part, in which the separate parts of my improvement are designated by the same reference characters in each of 25 the views, and in which—

Figure 1 is a side view of an elevator-car and the vertical corner guide-post thereof constructed according to my invention; Fig. 2, a bottom plan view of the car, the corner 30 guide-post between which the car moves being shown in section.

In the drawings forming part of this specification I have shown at 5 the corner guide-posts, between which the elevator-car moves, 35 and at 6 the elevator-car, and the bottom of this car is provided at a predetermined distance from each side thereof with a transverse bar 7 and at each side with a laterally-movable locking-bar 8, and these locking- 40 bars 8 are provided at each end with a pin 9, and said pins operate in connection with ratchet-teeth 10, formed on or secured to the post 5. Between each of the stationary bottom bars 7 and the corresponding laterally-movable locking-bars 8 is placed a strong 45 plate-spring 11, and these springs operate to force the locking-bars 8 outwardly, and at the ends of the bars 8 are transverse guide-pieces 12, between which and the bottom of 50 the car the locking-bars 8 move. Pivoted to each of the bars 7 at 13 are two levers 14,

and the outer ends of these levers are pivotally connected with links 15, which are pivoted to the locking-bars 8 at 16, and connected with the inner ends of each set of the 55 levers 14 is a flexible device 17, with each of which is connected a rope, cord, cable, or other flexible device 18.

The elevator-car 6 is provided at its opposite side, centrally thereof, and at the top and bottom thereof with pulley-wheels 19, and the ropes or other flexible devices 18 are passed upwardly around these pulley-wheels and connected with the car-supporting cable 20 at 21, and said car-supporting cable 20 passes over 65 pulleys 22 in the top of the elevator-shaft in the usual manner. The cable 20 is also connected with the top of the car, centrally thereof, as shown at 23, and that portion of said cable between the points 21 and 23 which is 70 designated by the reference character 20^a is of such length that in the operation of the car the ropes or cables 18 are drawn tight against the operation of the springs 11 before said part 20^a of the cable 20 is drawn 75 taut. In other words, a portion of the weight of the car in the operation thereof is placed on the ropes or cables 18, so as to withdraw the locking-bars 8 out of engagement with the ratchet-teeth 10, and in this position of 80 the parts the car will move up and down in the elevator-shaft between the corner guide-posts 5 in the usual manner. If in this operation the cable 20 should at any time be broken, the springs 11 will at once operate 85 to throw out the locking-bars 8, and the latter would engage with the ratchet-teeth 10 and stop the descent of the car; but as long as the cable 20 remains in working order, together with the ropes or cables 18, the locking- 90 bars 8 will be held in the position shown in dotted lines in Fig. 2 and will not operate to prevent the downward movement of the car.

It will thus be seen that I provide a safety attachment for elevator-cars which is simple in construction and operation and which is particularly designed to prevent the falling of the car if the cable which supports it should break, and by means of this construction I prevent the serious and sometimes fatal accidents which frequently accompany the breaking of the elevator-cable.

Having fully described my invention, what I claim as new, and desire to secure by Letters Patent, is—

1. The combination with an elevator-car, 5 provided with the usual supporting-cable, of laterally-movable spring-operated locking-bars mounted on the bottom of the car, levers pivotally supported beneath the bottom of the car and connected with said locking-bars 10 and flexible devices connected with said levers and passing upwardly around the car and connected with the supporting-cable, substantially as shown and described.
2. The combination with an elevator-car, 15 provided with the usual supporting-cable, of laterally-movable spring-operated locking-bars mounted on the bottom of the car, levers pivotally supported beneath the bottom of the car, and connected with said locking-bars 20 and flexible devices connected with said levers and passing upwardly around the car and connected with the supporting-cable, said

locking-bars being adapted to operate in connection with corner-posts in the elevator-shaft provided with ratchet-teeth, substantially as shown and described. 25

3. The combination with the vertical guide-posts of an elevator-car, which are provided with ratchet-teeth, of an elevator-car, locking-bars adapted to be brought into connection 30 with said ratchet-teeth, springs actuating the locking-bar, levers for actuating the locking-bar, and flexible devices connected with said levers passing up around the car and connecting with the supporting-cable of the car, 35 substantially as shown and described.

In testimony that I claim the foregoing as my invention I have signed my name, in presence of the subscribing witnesses, this 21st day of January, 1901.

CHARLES L. STARTUP.
